UNITED STATES PATENT OFFICE.

WILLIAM S. NOYES, OF CHICAGO, ILLINOIS.

DESIGN FOR A SPROCKET-WHEEL AND CHAIN GUARD.

SPECIFICATION forming part of Design No. 27,068, dated May 18, 1897.

Application filed March 9, 1897. Serial No. 626,682. Term of patent 3½ years.

To all whom it may concern:

Be it known that I, WILLIAM S. NOYES, a citizen of the United States, and a resident of Chicago, in the county of Cook and State of Illinois, have invented and produced a new and original Design for Sprocket-Wheel and Chain Guards or Shields for Bicycles, of which the following is a specification.

In the accompanying drawings, Figure 1 is a perspective of the guard embodying my design. Fig. 2 is a transverse section on the line 2 2 of Fig. 1.

A guard or shield of my design consists of a marginal frame A, the edges of which are continuous and unbroken or smooth, said margin having a flange A', which projects laterally therefrom in a direction, when applied to a bicycle, to cover the driving-chain.

At its front end a guard or shield of my design is provided with a circular web A², the

rear side of which is connected with the marginal frame A by webs or braces a. In the rear of the circular web A² the opposite sides of the marginal frame A are connected by plain webs or bridges a'.

A bead may be formed on the margin, as indicated by dotted lines.

I claim—

The design for a sprocket-wheel and driving-chain guard or shield, substantially as herein described and shown.

In testimony that I claim the foregoing as my invention I hereunto set my hand, this 3d day of March, 1897, in the presence of two witnesses.

WILLIAM S. NOYES.
